ABSORPTION REFRIGERATING APPARATUS

Glenn F. Zellhoefer, Bloomington, Ill.

Application February 23, 1935, Serial No. 7,662

1 Claim. (Cl. 62—119)

This invention relates to improvements in absorption type of refrigerating apparatus of the character disclosed in my prior co-pending application Serial No. 736,232, filed July 20, 1934.

5 The refrigerating apparatus so disclosed is particularly adapted to employ dichloromonofluoromethane as the refrigerant and ethyl ether or diethylene glycol acetate as the solvent. It has been found in practice that this refrigerant and 10 solvent will carry over into the receiver from one-tenth to three-tenths per cent of solvent even though the gaseous refrigerant in the rectifier is chilled as low as between 110 to 100° F., and an eliminator in the form of copper mesh 15 is used in the rectifier. Under these conditions, a refrigerating coil operating at 40° F. will carry at the outlet of the cooling coil a solution of solvent and refrigerant, and in this solution, it has been found there is between two to three 20 per cent of the total amount of refrigerant delivered to the coil even though the vapors are super-heated as much as 2° F.

It is an object of this invention to provide a means to liberate the refrigerant from the solvent as the solution leaves the cooling coil and before it is returned to the absorber and thereby effect an economy in operation.

With this and other objects in view, reference is made to the accompanying sheet of drawing 30 which illustrates in diagrammatical form the type of absorption apparatus disclosed in my said co-pending application and in detail the improved apparatus for effecting this economy with the understanding that minor detail changes may be made without departing from 35 the scope of this invention.

As this invention relates only to the means and method of liberating the refrigerant from that portion of the solution collected in the cooling coil of the apparatus, only the essential elements of the refrigerating apparatus need be described. In the apparatus illustrated in the diagram, the refrigerant and solvent form a solution in the absorber A. The solution is conveyed by the pipe 1 from the absorber through the heat exchanger HE and by pipe 2 to the heater H where the refrigerant is distilled or boiled off the solution and passes into the rectifier R while the solvent is returned by pipe 3 through the heat exchanger back to the absorber A. The refrigerant is conducted from the rectifier through the pipe 4 and passed through the condenser C into the liquid receiver R from which it is discharged in accordance with the 55 need of the cooling coil through the pipes 4 and

4^a to the expansion valve 5 connected with the manifold 6 of the cooling coil CC. The liquid refrigerant, being discharged under lower pressure in the cooling coil CC, returns to gaseous state and in so doing absorbs heat from the atmosphere surrounding the cooling coil. The gaseous refrigerant leaves the cooling coil through the manifold 7 and is conducted by the pipes 8 and 8^a back to the absorber A. The pipes 9 and 9^a, 10 and 10^a circulate cooling water through the 10 absorber A and rectifier R and the condenser C.

As stated hereabove with the particular refrigerant and solvent specified, a portion of the solution is carried over from the rectifier and will collect in the manifold 7 of the cooling coil. 15 To separate the refrigerant and solvent forming this solution, the gaseous refrigerant and the said solution collecting in the manifold 7 are discharged through the pipe 8 into one end of an additional heat exchanger 11, preferably of cylindrical form. The pipe 4, leading the liquid refrigerant from the liquid receiver R, is passed through one end of the additional heat exchanger 11 and is joined to a coil 12 contained within and of less diameter than the said additional 20 heat exchanger with the opposite end joined to the pipe 4^a leading from the opposite end of the additional heat exchanger 11 to the expansion valve 5 of the cooling coil.

It has been found that the liquid refrigerant 30 from the receiver passing through the coil 12 of the additional heat exchanger is ordinarily at a temperature ranging from 85-95° F. and the solution of the refrigerant and solvent delivered from the manifold 7 into the additional heat exchanger 11, in passing over the warm surface of the coil 12 will liberate nearly all of the refrigerant from the solution and the cooling effect therefrom is conserved as the refrigerant delivered through pipe 4^a into the cooling coil is at 35 a lower temperature than that delivered through pipe 4 into the additional heat exchanger 11. In addition to the cooling effect of the liquid refrigerant due to the vaporization of the refrigerant from the solvent within the additional heat 40 exchanger 11, there is also some cooling effect derived by super-heating the vaporized refrigerant in passing over the coil 12. Furthermore, under certain conditions, there is a tendency for a dry expansion coil or cooling coil to flood at 45 times, and, by the addition of this additional heat exchanger 11, connected in the manner shown to the discharge side of the cooling coil, effects the vaporization of the refrigerant in part or "in toto" that is flooded through the manifold 7 of 55

the cooling coil. While the amount of cooling of the liquid refrigerant depends upon operating conditions and the size of the coil, it is estimated that the inclusion of the additional heat exchanger 11 effects an economy ranging from five to twenty per cent.

What I claim is:

In an absorption refrigerating apparatus including an absorber, a heater, a heat exchanger 10 between the absorber and the heater, a cooling coil, a condenser between the heater and cooling coil, with means for passing the solution of refrigerant and solvent through the heat exchanger into the heater and means for passing 15 the refrigerant liberated from the solution from the heater through the condenser and cooling coil to the absorber while returning the solvent from which the refrigerant has been liberated

in the heater through the heat exchanger to the absorber to form solution therein with the returned refrigerant, the provision of a chamber opening into the cooling coil through which the refrigerant passes on its way from the cooling coil to the absorber and the provision of a coil within said chamber through which the refrigerant passes on its way from the condenser to the cooling coil, whereby flooding of the cooling coil is prevented and the cooling effect produced within the chamber by the liberation of refrigerant from the solution collected therein by the passage of the refrigerant and carried over solution through the coil within the chamber reduces the temperature thereof as it leaves 15 said coil on its way to the cooling coil.
